UNITED STATES PATENT OFFICE.

FRÉDÉRIC WULLYAMOZ, OF LAUSANNE, SWITZERLAND.

STARTING-GEAR FOR MOTOR-CARS.

1,166,105.

Specification of Letters Patent. Patented Dec. 28, 1915.

Application filed October 29, 1913. Serial No. 797,953.

To all whom it may concern:

Be it known that I, DR. FRÉDÉRIC WULLYAMOZ, a citizen of Switzerland, residing at Lausanne, Canton of Vaud, in the Confederation of Switzerland, have invented certain new and useful Improvements in Starting-Gears for Motor-Cars, of which the following is a specification.

There are various types of starting gear for motor cars operated from the driver's box, and I am also aware that there are starting gears for motor cars operated by a lever and toothed segment. But in all these devices, so far as I am aware, the starting lever is so arranged that the driver must push it away from him or at least, in operating the same, the driver makes use of the strength of his arms alone.

The object of the present invention however is the provision of a starting device operated from the driver's box by the simultaneous use of the arms and legs of the driver, and this is obtained by employing a gear so arranged that the driver has to draw a starting lever toward himself and at the same time press on a pedal, which, by means of suitable gears, acts on the same toothed segment and in the same direction as the starting lever does.

The accompanying drawings show several forms of my invention, and in which—

Figure 1 is a sectional elevation illustrating one form of my improved starting mechanism. Fig. 2 is an enlarged elevation and partial section illustrating the manner in which the pinion, as illustrated in Fig. 1, is attached to the engine shaft. Fig. 3 is a sectional elevation illustrating another form of my starting mechanism. Fig. 4 is a sectional plan of the same, the section being taken on line C, D, Fig. 3, and Fig. 5 is a sectional elevation, the section being taken on line A, B, Fig. 3.

Referring to Figs. 1 and 2, 2 represents a starting lever secured to the shaft *b*, and is provided with a toothed segment *d* at the end of a curved arm *i*. The segment *d*, at times, meshes with the pinion *e* which is fitted loosely to the driving shaft *c* of the motor. The arm *i* is bent to pass over a shaft *b'*, to which is secured the usual pedal *f* of the accelerator of the motor. On this same shaft is mounted loosely a pedal *a'* which is integral with a toothed segment *g* meshing with a toothed segment *e'* secured on the

shaft *b*. The toothed segment *d* is only in gear with the pinion *e* when the motor is to be started and at other times, that is, before and after the starting of the car they are out of gear and the starting lever at rest. The pinion *e*, fitting loosely on the shaft *c*, is fast to a cylindrical casing *m* containing a ratchet wheel *n* fast to the shaft *c* and two pawls *m'* carried by the casing and engaging the ratchet wheel. When the driver pulls the lever *a* by hand and depresses the pedal *a'* in the direction indicated by the arrow, he thereby throws the segment *d* into gear with the pinion *e* and rotates the shaft *c* by means of the pawls *m'* and the ratchet wheel *n*, and starts the motor. By this contrivance, much power will be brought into action, making it possible to employ a relatively large gear ratio between the shaft *b* and the pinion *e*, which will make the pinion *e* turn rapidly and insure the starting of the motor. Instead of the ratchet and pawls, any other suitable coupling device may be employed in order to produce the same result, and also the gearing between the pedal *a'* and the toothed segment *d* may be made in any other suitable manner without departing from the nature of the invention.

Referring to Figs. 3, 4 and 5, *a* is the manually operated starting lever and *a'* the starting lever acted upon by the foot. Both these levers actuate one and the same pinion *e'* which is a part of a rocking lever *i*, the end of which carries a toothed segment *d* in gear with a conical pinion *e* fixed to the shaft *c* of the motor. The rocking lever *i* is supported in its rocking movements by a guide roller *p* the socket of which is fixed to the frame of the machine. The toothed segment *d* is not firmly fixed to the end of the rocking lever *i* but connected to the same by means of a device which is shown separately in Fig. 5 of the drawing. The end *i'* of lever *i* is of U-shaped section as shown in Fig. 4 and has a bottom-portion *i''* intended to limit the stroke of the toothed segment *d* hinged to the end *i'* by means of links *k* guided by the U-shaped head of *i'*. There is further provided a spiral-spring *l* which tends to maintain the toothed segment *d* in its lower position, in which it rests upon the bottom *i''* of the end *i'*. A cap *o* is fixed to the toothed segment *d* and has on one side a projecting guide *o'* the

lower end of which is bent as shown at o^2 and o^3 in Fig. 5. This guide o' coöperates with a catch q acted upon by a spiral spring q^2 located in a tubular casing q' fixed to 5 the frame of the machine. The catch q acts upon the guide o' as shown in dotted lines in Fig. 5, to retract the toothed segment d out of reach of the teeth of the pinion e when the rocking lever i is caused 10 to return to its starting position, as shown in full lines in said figure. It will be seen in this same Fig. 5 that the roller p is placed so as to support the lever i in those parts of its strokes in which the toothed segment d 15 engages the pinion e . When the starting lever is at rest the arm i and segment d will have the positions as shown in Fig. 3 and in Fig. 5 in full lines, the bar d' resting on the shoulder i^3 and the segment d being out of 20 gear with the pinion e . When the driver pulls the starting lever a , and at the same time depresses the pedal a' the arm i will swing upward and the segment d will be thrown into gear with the pinion e , the 25 back-side of the arm i rolling on the guide roller p and the blade o' sliding on the outward side of the pin q which is solidly fixed on a cylindrical sliding piece yieldingly secured by means of the spring q' within a 30 casing q^2 fixed on the frame of the car. When the segment d continues its movements upward, the shoulder o^2 meets the pin q , pushing it aside until the bottom piece o^3 is freed. The toothed segment d 35 is then no longer in gear with the pinion e , and the arm i is at the upper end of its travel so that the pin q slides back into its initial position. By this operation the motor will have been started in the same way 40 as has been described for Figs. 1 and 2, and the driver may now let the starting lever a and the pedal a' return to their initial positions, whereupon the segment d and the arm i will return by their own weight 45 into their initial positions of rest without interfering with the pinion e which in this case is keyed to the driving shaft of the motor. Before the toothed segment d , when moving downward, will have reached the 50 pinion e , the bottom piece o^3 will have reached the pin q and sliding on its inner side the shoulder o^2 will force the bar d' to swing around until it comes into contact with the bar i' , thereby moving the segment d out of the path of the pinion e to 55 the position as shown in dotted lines in Fig. 5, the spring l then connecting the two bars d' and i' in such a way that it will help to overcome the weight of the bar d' . 60 Before the arm i reaches its initial position of rest and after the blade o' has left the pin q , the bar d' swings back, dropping by its own weight, until it rests again on the shoulder o^3 , notwithstanding the action of

the spring l which is only adjusted so as to 65 break the fall and prevent shock.

I claim as my invention—

1. A starting mechanism for motor vehicle engines comprising a shaft, a pinion on the same, a hand lever, an arm connected 70 to the hand lever, a rack gear, means for pivotally connecting the said rack gear in the free end of the said arm, means for yieldingly maintaining the said rack gear normally against the end of the said arm so 75 that when moved in one direction the said rack will engage the said pinion, and means operative when the lever and arm are moved in the opposite direction for causing the said rack to clear said pinion. 80

2. A starting mechanism for motor vehicle engines comprising a shaft, a pinion on the same, a hand lever, an arm connected to the hand lever, a rack gear, links by which the said rack gear is pivotally connected to the free end of the said arm, a spring for normally maintaining the said rack gear in position against the free end of the said arm so that when the said arm and hand lever are actuated in one direction the 90 said rack gear meshes with the said pinion, and means operative when the said lever and arm are moved in the opposite direction for causing the said rack to clear the said pinion. 95

3. A starting mechanism for motor vehicle engines comprising a shaft, a pinion on the same, a hand lever, an arm connected to the hand lever, a rack gear, links by which the said rack gear is pivotally connected to the free end of the said arm, a spring for normally maintaining the said rack gear in position against the free end of the said arm so that when the said arm and hand lever are actuated in one direction 100 the said rack gear meshes with the said pinion, a yieldingly mounted pin, and a plate carried by the said rack gear and adapted to engage with the said yieldingly mounted pin to swing and maintain the said rack gear 110 out of engagement with the pinion when the said arm and hand lever are moved in the opposite direction. 110

4. A starting mechanism for motor vehicle engines comprising a shaft, a pinion 115 on the shaft, a hand lever, a foot lever, an arm connected to and operated by the simultaneous movement of the said hand and foot levers, a rack gear yieldingly mounted in the end of the said arm and adapted when the 120 said hand and foot levers and arm are moved in one direction to engage the said pinion, and means operative when the said hand and foot levers and arm are moved in the opposite direction for causing said rack 125 to clear said pinion.

5. A starting mechanism for motor vehicle engines comprising a shaft, a pinion

- on the shaft, a hand lever, a foot lever, an arm connected to and operated by the simultaneous movement of the said hand and foot levers, a rack gear, means for yieldingly mounting the said rack gear in the free end of the said arm, means for normally maintaining the said rack gear against the free end of the said arm so that when the said hand and foot lever and arm are moved in one direction the said rack engages the said pinion, and means operative when the said hand and foot levers and arm are moved in the opposite direction for causing the said rack to clear said pinion.
6. A starting mechanism for motor vehicle engines comprising a shaft, a pinion on the shaft, a hand lever, a foot lever, an arm connected to and operated by the simultaneous movement of the said hand and foot levers, a rack gear, links by which the same is pivotally mounted in the free end of the said arm, a spring for normally maintaining the said rack gear against the free end of the said arm so that when the said hand and foot levers and arm are moved in one direction the said rack gear engages the said pinion, a yieldingly mounted pin, and a plate connected to the said rack gear and adapted to engage the said yieldingly mounted pin to swing the said rack gear from and maintain the same out of contact with the said pinion when the said hand and foot levers and arm are moved in the opposite direction.

In testimony whereof I have affixed my signature in presence of two witnesses.
